CLOSURE DEVICE

Clarence W. Shaw, Detroit, Mich., assignor, by
mesne assignments, to Eaton Manufacturing
Company, Cleveland, Ohio, a corporation of
Ohio

Application March 2, 1936, Serial No. 66,608

14 Claims. (CL 220—40)

This invention relates to closures for fluid containing receptacles, and more particularly to closures of the type adapted for releasable sealing connection with a filler neck or opening of the 5 receptacle.

An object of this invention is to provide an improved closure device of such simplified form that its relatively few parts can be very economically manufactured and assembled.

10 Another object of the invention is to provide an improved closure device having a cover member provided with inwardly extending portions adapted to cooperate with external locking cams of a filler neck, and also having an inner cover member relatively freely movable in all directions in the outer cover member and retained therein only by said projections.

15 A further object of the invention is to provide an improved closure device, of the type referred to, wherein the inner cover member is resilient and of disk-like form and has a substantially central fulcrum projection about which the relative rocking of the outer and inner cover members takes place.

20 Yet another object of this invention is to provide an improved closure device embodying an air chamber and having novel means for efficiently venting a fluid container through such air chamber substantially without loss of liquid through 25 the vent means.

25 Still another object of this invention is to provide an improved closure device, of the type referred to, wherein the inner cover structure comprises a pair of cooperating members providing 30 an air chamber therebetween and shiftably retained in the outer cover member by the cam engaging projections thereof, and wherein novel means is provided for venting a fluid containing receptacle through said air chamber.

35 Other objects and advantages of the invention will be apparent from the following description, when taken in conjunction with the accompanying sheets of drawings, wherein—

40 Fig. 1 is a vertical sectional view taken through a closure device embodying my invention and showing such device applied to a filler neck.

45 Fig. 2 is a bottom plan view showing the closure of Fig. 1 in detached relation.

50 Fig. 3 is a plan view of the resilient disk-like member which forms a part of my improved closure device.

55 Fig. 4 is a vertical sectional view of another closure embodying my invention and showing the same applied to a filler neck.

55 Fig. 5 is a similar vertical sectional view show-

ing still another closure embodying my invention.

Fig. 6 is a detached plan view of a cup-like member forming a part of the inner cover structure of Fig. 5.

Fig. 7 is a partial sectional view taken on line 5 1—7 of Fig. 6 and showing one of the hooded vents.

Fig. 8 is a plan view showing a filler neck to which my improved closure may be applied.

Fig. 9 is a side elevation thereof.

Fig. 10 is a vertical sectional view showing my invention embodied in another novel closure device which is applicable to vehicle radiators or the like.

Fig. 11 is a transverse sectional view thereof taken on line 11—11 of Fig. 10.

Fig. 12 is a vertical sectional view showing my invention embodied in still another closure device.

Fig. 13 is a bottom plan view of the closure in 20 detached relation with the inner cover member removed therefrom, and

Fig. 14 is a sectional view taken on the line 14—14 of Fig. 13.

More detailed reference will now be made to the accompanying drawings which illustrate preferred forms of my improved closure device, but before proceeding with such detailed description I desire it to be understood that my invention may be embodied in various other closure devices and venting arrangements than the particular ones 30 herein disclosed.

My invention is especially applicable to closure devices of the quick detachable bayonet-type, such as are more or less commonly used on radiator and fuel tank openings of motor vehicles. Fluid containers of this type are usually provided with a tubular filler neck, and I have shown my improved closure device as applied to such a neck.

40 Figs. 8 and 9 of the drawings show a suitable filler neck of this type to which my closure device may be applied. This filler neck comprises a tubular member 10, which may be a part of or connected with the fluid container, and which has an external annular flange 11 at its outer end. This external flange forms an annular gasket seat and carries a plurality of circumferentially spaced arcuately extending locking cams 12 adapted to be engaged by suitable means of the closure device for releasably connecting the same with the neck. These locking cams may be formed on downwardly and outwardly extending portions of the external flange 11 to extend between the openings 13 thereof which accommodate the projections of the closure device when the latter is applied to the neck. Each of the cams may be pro- 55

vided with a depending stop 14 adjacent one end thereof and with a dwell portion 15 adjacent the stop.

The closure itself comprises an outer cover member 18 which is adapted for releasable locking cooperation with the filler neck 10, and an inner cover structure 19 which presses an annular gasket 20 into sealing engagement with the gasket seat of the neck during such locking cooperation. The outer cover structure 18 may be in the form of a generally circular closure body having a transverse top wall 21 of spheroidal or other desired shape, and a depending annular marginal skirt 22. For releasably connecting the closure device with the filler neck I provide the skirt 22 of the outer cover member with inwardly extending lugs 23 which cooperate with the locking cams 12 in a manner now well understood in this art. The lugs 23 are of a size and shape to pass through the openings 13 of the filler neck and are spaced circumferentially of the depending skirt 22 a distance corresponding substantially with the spacing of such neck openings.

The inner cover structure 19 may comprise a pair of oppositely dished upper and lower members 25 and 26 in cooperating relation to provide an air chamber 27 therebetween. The member 25 may be a generally circular or disk-like resilient metal member. In accordance with my invention, either the transverse wall 21 of the outer member or the member 25 has an upstanding substantially central projection 28 for bearing or fulcruming engagement with the other member. This central projection may be an elevated integral part of the cover member, in this particular instance the cover member 25, and may have a substantially flat top. The member 25 may have a substantially flat central body portion 29 surrounding the projection 28, and may also have an annular marginal flange 30 which is integrally connected with the flat portion 29 by the downwardly and outwardly extending annular shoulder portion 31. The annular flange 30 is preferably deflected or inclined with respect to the flat portion 29 so that this flange extends upwardly as well as outwardly, as is clearly illustrated in Fig. 1 of the drawings.

The member 26 has a downwardly dished or cup-like portion which extends into the opening of the filler neck when the closure device is applied thereto and an annular marginal flange 33 which presses the gasket 20 against the gasket seat of the filler neck. The cup-like portion of this member may be constructed with a spheroidal bottom wall 34 and with a substantially cylindrical side wall portion 35 which connects the spheroidal bottom wall portion with the annular flange 33. The cylindrical wall portion 35 may be of a diameter, in relation to the internal diameter of the filler neck, to enable the cup-like portion of the member 26 to function as a pilot means when the closure device is applied to the neck. The marginal flange 33 of this member preferably extends upwardly and outwardly in substantially the same angular relation as the flange 30 so as to have a complemental and more or less sealing engagement therewith.

The inner closure structure formed by the members 25 and 26 is relatively freely movable in all directions in the outer cover member and is retained therein only by the cooperation of the inwardly extending lugs 23 with the marginal flanges 33 and 30. This relatively free movement between the inner and outer cover structures 75 is very desirable because it permits the lugs 23

of the outer cover member to readily cooperate with the locking cams of the filler neck as the closure device is applied thereto and, at the same time, enables the inner cover structure to position itself relative to the outer end of the filler neck and to press the gasket 20 into efficient sealing engagement with the seat thereof. The relative movement which takes place between the inner and outer cover structures during the application of the closure device to the filler neck is, in part, a relative rocking about the fulcrum projection 28. Such relative rocking between the inner and outer cover structures may be limited, to an extent desired, by the engagement of the upwardly and outwardly extending marginal flange 30 with the transverse top wall of the outer cover member. In addition to the function of limiting the relative rocking between the inner and outer cover structures, the inclination of the flanges 30 and 33, provided by having them extend upwardly and outwardly as explained above, is desirable because it causes the gasket 20 to be pressed against an annular portion of the filler neck which lies inwardly of the openings 13.

In what I now regard to be a practical form of construction for my improved closure device, I provide the annular skirt 22 with three of the inwardly extending lugs 23 and also provide the filler neck with three equally spaced locking cams 12. When the outer cover member 18 is provided with three such lugs I find that the members 25 and 26 of the inner cover structure and the gasket 20 can be very easily assembled into the outer cover member without the need of tools of any kind whatever. This is accomplished by inserting the members and the gasket 20 beneath two of the lugs and then deflecting the members and gasket slightly so as to pass the third lug. To facilitate this assembly operation one or both of the members 25 and 26, but preferably only the member 25, may be provided with a flat or chord-like portion 36 at some one point of its circumference, as shown in Fig. 3 of the drawings.

When my improved closure device of Fig. 1 is to be used on certain fluid containers, such as the fuel tanks of motor vehicles, it may be desirable to provide for venting of the tank through the closure device. I find that such venting can be very expeditiously and efficiently accomplished through the air chamber 27 by providing relatively restricted vent passages 38 and 39. The vent passage 38 is a relatively restricted passage adjacent the top of the air chamber 27, preferably being formed through the central projection 28 of the member 25. The vent passages 39 are also relatively restricted passages, but are located adjacent the bottom of the air chamber 27, preferably extending through the lowest part of the spheroidal portion 34. The vent passage 38 leads to atmosphere around the outer edges of the marginal flanges 30 and 33 and the gasket 20. The vent passages 39 connect the air chamber 27 with the interior of the tank.

In connection with the inner cover structure formed by the members 25 and 26, it will be noted that the air chamber 27 is of relatively large capacity or volume, and this is an important and desirable feature in connection with my venting means. It might well be explained at this point that when motor vehicles turn corners rapidly 70 there is often a tendency for fuel to be forced out of the tank through the vent openings of the tank closure. However, in the improved closure structure which I have provided the escape of fuel through the vent opening 38 cannot occur 75

unless the cup portion 34 has been substantially filled by the passage of fluid through the vent openings 39 as the result of surging of the fuel against the closure device. Since the vent openings 39 are relatively restricted it will be seen that a substantial time element is involved in the passage of fuel through these openings, such that the surging of the fuel will have ceased before the chamber 27 becomes full and the fuel which has already passed into this chamber will be sucked or withdrawn therefrom back into the fuel tank.

As explained above the venting of the chamber 27 takes place around the outer edge of the gasket 20 and, when this venting arrangement is employed, it may be desirable to provide the outer edge of the gasket with notches or serrations 40 which provide air passages between the outer edge of the gasket and the depending skirt 22. These notches insure the presence of an air passage between the edge of the gasket and the skirt in the event that the gasket expands sufficiently to press the outer edge thereof against the skirt.

It will be understood, of course, that in the cooperation of my improved closure structure with the filler neck, the locking and unlocking is accomplished by relative rotary movement therebetween, and from the arrangement as illustrated in Fig. 1 and just described, it will be readily seen that the rotative force required to produce such locking or unlocking is very low, because the inner closure structure and gasket do not rotate relative to the neck but are merely pressed in sealing engagement therewith by the outer cover member. In applying a closure device to a filler neck having external cams it sometimes occurs that one of the cam engaging projections of the closure will ride on top of the flange of the neck instead of engaging under the cam 12, and this condition prevents proper sealing engagement of the closure with the neck. In my improved closure device such improper assembly is prevented by limiting relative rocking between the outer and inner cover members and by certain proportioning of the cooperating parts.

The relative rocking between the inner and outer cover members may be limited, as explained above, by having the annular marginal flange 30 extend upwardly and outwardly to be engaged by the top of the outer cover member during relative rocking. As to the proportioning of the parts, I find that very good results are obtained when I construct my closure device so that the clearance space 41 bears a more or less definite relation to the vertical distance 42 between the top of the neck flange and the starting portion of the cam 12. If the height of the clearance space 41 is approximately one-half of the distance 42, as measured with the closure on the neck but prior to locking rotation thereof, I find that the relative rocking between the outer and inner cover members is limited to an extent which prevents one of the locking projections from riding on top of the neck flange.

When my improved closure device is to be applied to a receptacle which does not require venting or which has independent venting means, the vent passages 38 and 39 may be omitted, or, if desired, the vent opening 38 and the member 26 of the inner cover structure may be omitted. In Fig. 4 of the drawings I have shown my invention embodied in such a simplified form of closure device from which the venting feature has been omitted. This closure device is provided

with an outer cover member or body 45, generally similar to the outer cover member 18 of Fig. 1, except that it may have a substantially flat transverse top wall 46. The outer cover member 45 has inwardly extending lugs 47 adapted to cooperate with locking cams 48 of a filler neck 49 to which the closure device may be applied. An annular sealing gasket 50 may be pressed against the outer end of the filler neck by an inner cover member 51.

The inner cover member 51 may be a resilient disk-like metal part generally similar to the member 25 of Fig. 1 and having a localized central fulcruming projection 52 for engagement with the transverse top wall 46 of the outer cover member and an upwardly and outwardly extending annular marginal flange 53 for limiting relative rocking between the inner and outer cover members and for pressing the annular gasket 50 against the filler neck. The inner cover member 51 has relatively free movement in all directions in the outer cover member 45 and is retained therein only by the inwardly extending lugs 47 of the latter member.

In Figs. 5 and 6 of the drawings I have shown my invention embodied in a closure device which is generally similar to that of Fig. 1 but which provides a somewhat different venting arrangement. This closure device comprises outer and inner cover members 55 and 56 and is adapted to be releasably connected with a filler neck 57 by inwardly extending projections 58' of the outer cover member cooperating with external locking cams of the neck. The inner cover structure comprises cooperating oppositely dished members 58 and 59 having a vent chamber 60 therebetween. These members have annular marginal flanges 61 and 62 in cooperating relation with each other and which press the annular sealing gasket 63 against the outer end of the filler neck. The member 58 is provided substantially centrally thereof with a localized fulcruming projection 64 which engages the top wall of the outer cover member 55 and about which relative rocking between the inner and outer cover members takes place.

My improved venting arrangement, as embodied in this closure device, includes vent passages 66 and 67 which provide for venting of the fluid container with which the closure device is used through the air chamber 60. The vent passage 66 is a relatively restricted passage adjacent the top of the chamber 60, preferably being formed through the fulcruming projection 64. The vent passages 67 are relatively large passages formed through the substantially flat bottom wall of the cup portion of the member 59. These relatively large vent passages 67 are preferably each provided with a deflecting hood 68 which may be formed integral with the bottom wall of the cup portion by shearing and deflecting metal thereof at certain points. These vent hoods are preferably contained in the air chamber 60 and are preferably disposed in a circumferentially extending series, as shown in Fig. 6. The hoods are individually disposed so that each hood will cause fluid which passes through its opening 67 to be directed toward the side wall of the chamber 60 substantially tangentially thereof. As indicated in Fig. 6, the hoods may be arranged in the series so that the tangential discharge of fluid through the openings 67 will tend to cause rotation of the fluid in the air chamber.

By reason of the arrangement of the hoods as just described, it will be seen that fluid can read-

ily pass into the air chamber 60 through the vent openings 67 when surging occurs in the fuel tank, but that the flow of fluid into the air chamber is directed laterally instead of toward the restricted vent opening 66 and the velocity of the discharge is dissipated in producing a rotary movement of the fluid in the air chamber. When the surging of fluid in the tank ceases, the relatively large vent openings 67 permit fluid to readily drain back into the tank from the chamber 60. I have found that this venting arrangement substantially eliminates loss of fluid from a tank to which this closure device is applied and yet permits efficient venting of the tank for the desired withdrawal of fluid therefrom.

The closure device and the venting means shown in Figs. 5 and 6 are especially useful on relatively short, large diameter necks, such as are often provided on the fuel tanks of tractors. Such fuel tanks are often located close to the engine and are frequently exposed to the sun's rays. These conditions tend to cause vapor to be generated in substantial volume in the tank and forced out through the vent openings. Such outflow of vapor tends to carry fuel out through the vent openings, especially when the fuel surges or is splashed about in the tank as would occur during the operation of a tractor. In my novel venting arrangement such loss of fuel does not occur because fuel is not trapped in the air-chamber but drains freely therefrom, and because the flow of fuel into the air chamber is deflected away from the top vent passage.

In Figs. 10 and 11 I show my invention embodied in another closure device which is especially suitable for use on vehicle radiators and the like. In the particular form of this closure device herein illustrated, I show a tank or radiator 70 having a tubular filler neck 71 to which the cap is applied. The filler neck has external locking cams 72 and is provided with an annular gasket seat 73 at its outer end. Adjacent its inner end the neck is provided with a laterally extending flexible metal washer 74 with which a part of the cap cooperates to provide a seal axially inwardly of the seal provided by the engagement of the gasket 75 of the cap with the annular gasket seat. At a point between the seal provided by the gasket 75 and the seal provided by the flexible washer 74, the neck has a vent and overflow opening 76 to which one end of a drain tube 77 may be connected.

The closure itself comprises an outer cover member 79 and an inner cover member which is composed of complementary parts 80 and 81. These complementary parts of the inner cover member are shaped to provide an air chamber 82 therebetween, and are provided with upwardly and outwardly extending annular marginal flanges 83 and 84 which sealingly engage each other and press the gasket 75 against the gasket seat of the neck. The member 80 may be a resilient disk-like metal member which has rocking or fulcruming engagement with a depending central projection 85 of the outer cover member. The member 81 may be a hollow depending part having more or less the shape of a truncated cone. The inner cover structure formed by the members 80 and 81 is relatively freely movable in the outer cover member 79 but is retained therein by the inwardly extending lugs 86 which cooperate with the external locking cams of the neck.

As shown in Fig. 10, the depending member 81 of the inner cover structure extends into the opening of the neck with its wall spaced from the

wall of the neck to provide an annular vent chamber 87 therebetween. The vent passage 76 of the neck communicates with this chamber, and the chamber 82 of the inner cover structure may also communicate with this chamber through vent openings 88. The latter vent openings are formed through the member 81 preferably at a relatively high point thereof. The lower end of the depending member 81 is formed with an annularly extending shoulder 89 which engages and deflects the flexible washer 74 when the closure is applied to the neck. The parts are so constructed and arranged that this shoulder engages the washer 74 to provide an inner seal at the same time that the gasket 75 is pressed against the seat 73 of the neck to provide the outer seal.

The lower end of the depending part 81 may be provided with a tubular extension 90 which extends into or through the opening of the washer 74. This extension is provided with an opening at the bottom thereof which communicates with the interior of the tank or radiator but which is normally substantially closed by a check valve element. The check valve element employed in this instance is a ball 91 adapted to be normally held in its closed position by gravity. A restricted vent passage may be provided past the check valve ball 91, preferably in the form of a V-notch 92 cut into the edge of the valve seat.

From the closure construction just described it will be seen that the radiator or tank 70 is normally vented to atmosphere through the V-notch 92, air chamber 82, vent passages 88, annular chamber 87, passage 76, and drain tube 77. During ordinary operating conditions, the venting takes place as just traced without opening of the check valve 91. However, if pressure should develop in the radiator, such as might result from the generation of steam or expansion of the coolant, the check valve 91 will be opened and the pressure will be relieved to atmosphere through the openings 88, the chamber 87, and the drain tube 77.

In Figs. 12, 13 and 14, I have shown my invention embodied in another closure device of the type having external locking means but wherein the outer cover structure is of somewhat different construction. In this latter form of closure device, I show a filler neck 95 having external locking cams 96 and an annular seat 97 against which the gasket 98 of the closure may be pressed.

The closure itself includes a resilient disk-like inner cover member 99 having an upwardly and outwardly extending annular marginal flange 100 for pressing the gasket against the seat of the neck. The closure also includes an outer cover member comprising a body member 101 and a shell 102 of more or less ornamental character which is mounted on such body member. According to my invention, the body member 101 is of relatively large diameter and has a plurality of spaced arcuately extending arms 103 depending around the inner cover member 99 and provided with inwardly projecting lugs 104 for cooperation with the locking cams of the neck. These depending arms 103 are formed from sections partially sheared from the top wall of the body member. To illustrate how these arms are formed by partially shearing and downwardly deflecting the sections of metal, I have shown by the dot and dash line 105 in Fig. 13 where the shearing of the metal would take place. The openings, from which the arms 103 have been sheared, may be shaped and enlarged as desired by trim-

ming to provide the smooth oval-shaped openings 106 shown in Fig. 13. The top wall of the body member 101 from which the arms 103 have been thus sheared and deflected, may be reenforced if desired by providing the same with one or more radially extending ribs 107. The top wall of this member may also be provided centrally thereof with a localized depending fulcruming projection 108 which engages the inner cover 10 member 99.

As shown in Fig. 12, the body member 101 may have a depending annular flange or skirt 110 spaced outwardly from the depending arms 103 and around which a skirt portion 112 of the shell 15 102 may be crimped.

From the foregoing description and the accompanying drawings it will now be readily understood that I have provided an improved closure device of such simplified construction that the 20 relatively few parts thereof can be very economically manufactured and assembled. It will be further understood that in my improved closure device provision is made for relatively free movement between inner and outer cover members, 25 and that this relative movement enables lugs of the outer cover member to cooperate with external locking cams of a filler neck while the inner cover member sealingly cooperates in an efficient manner with the gasket seat of the neck. It will also 30 be readily understood that I have provided a novel venting arrangement adapted to be embodied in a closure device of simplified construction and which provides for efficient venting of a receptacle substantially without loss of fluid therefrom, 35 even though the contents of the receptacle may be subjected to violent surging.

While I have illustrated and described the improved closure and venting means of my invention in a somewhat detailed manner, it will be understood, of course, that I do not wish to be limited to the precise details of construction and arrangements of parts herein disclosed, but regard my invention as including such changes and modifications as do not constitute a departure from 45 the spirit of the invention and the scope of the appended claims.

Having thus described my invention, I claim:

1. In a closure for a receptacle neck having external cam locking portions thereon, a closure body having inwardly extending cam engaging portions for locking cooperation with the cam portions of the neck, and an inner cover member normally retained in said closure body by said inwardly extending portions and adapted to sealingly engage said neck during said locking cooperation, said inner cover member being resilient and having a localized fulcrum projection substantially centrally thereof for engagement with the closure body and a marginal portion adapted to 50 cooperate with the closure body for limiting relative rocking of the closure body and the inner cover member about said fulcrum projection.

2. In a closure for a receptacle neck having external cam portions thereon, an outer cover member having a depending annular skirt provided with spaced inwardly extending portions for locking cooperation with said cam portions, and a flexible metal inner cover shiftably retained in the outer cover member and adapted for sealing engagement with said neck, said inner cover being 55 upwardly dished and having a substantially flat central portion provided with an elevated localized projection centrally thereof and also having an upwardly and outwardly extending marginal flange.

3. In a closure of the bayonet joint type, a neck having external locking cams, a closure body having a depending annular skirt provided with inwardly projecting cam engaging portions, an upwardly dished resilient inner cover relatively freely movable in said body and having an upwardly and outwardly extending annular marginal flange providing a relatively inclined gasket seat, said inner cover also having an integral localized central projection directly engageable with the closure body to provide for relative rocking therebetween and being retained in said body only by cooperation of the cam engaging portions thereof with said flange, and a gasket adapted to be sealingly pressed against 10 the neck by said flange.

4. In a closure for a receptacle neck having external locking means, a closure body having inwardly extending lugs for locking cooperation with the locking means of said neck, and an inner cover shiftable in said closure body and adapted for sealing engagement with said neck during said locking cooperation, said inner cover comprising upper and lower oppositely dished members defining an air chamber therebetween 20 and one of which projects beyond the inner portions of said lugs for retaining the inner cover in said closure body, said upper member being resilient and adapted to flex during said locking cooperation.

5. In a closure for a receptacle neck having external locking means, a closure body having inwardly extending means for locking cooperation with the locking means of said neck, an inner cover shiftable in said closure body and adapted for sealing engagement with said neck during said locking cooperation, said inner cover comprising cooperating members defining an air chamber therebetween and having portions extending beyond the inner portions of the locking means 30 of the closure body for retaining the inner cover therein, one of the members having a depending cup portion and the other being resilient and having an elevated central projection engageable with said body.

6. In a closure for a receptacle neck having external locking means, a closure body having inwardly extending means for locking cooperation with the locking means of said neck, a gasket, an inner cover shiftable in said closure body and adapted to press the gasket against the neck for sealing engagement with said neck during said locking cooperation, said inner cover comprising members defining an air chamber therebetween and having annular marginal flanges engaging each other, said flanges providing a seat for said gasket and extending beyond the inner portions of the locking means of the closure body for retaining the inner cover therein, one of the members having a depending cup portion and the other being a resilient disk having an elevated central projection adapted for pivotal bearing engagement with the closure body during said locking cooperation.

7. In a closure for a receptacle neck having external locking means, a closure body having inwardly extending means for locking cooperation with the locking means of said neck, an inner cover shiftable in said closure body and adapted for sealing engagement with said neck during 70 said locking cooperation, and projecting beyond the inner portions of the locking means of said closure body whereby the inner cover is retained in the closure body, said inner cover comprising members defining an air chamber therebetween 75

and having annular marginal flanges engaging each other, one of said members having a spheroidal portion adapted to extend into the neck and a substantially cylindrical portion connecting said spheroidal portion with the marginal flange and the other member having an upwardly extending central projection engageable with the closure body.

8. In a closure for a receptacle neck having external cams, a closure body having a depending annular skirt provided with inwardly extending locking members adapted to cooperate with said cams, and an inner cover comprising a pair of oppositely dished members providing an air chamber therebetween, said inner cover projecting beyond the inner portions of the locking members of the closure body and being thereby retained in the latter, said dished members having cooperating annular marginal flanges and having relatively free movement in said closure body, one of said dished members being resilient and having localized pivotal bearing contact with the closure body during locking cooperation of the latter with the neck.

9. In a closure for a receptacle neck having external locking means, a closure body having inwardly extending means for locking cooperation with the locking means of said neck, an inner cover shiftable in said closure body and adapted for sealing engagement with said neck during said locking cooperation, said inner cover comprising members defining an air chamber therebetween and having annular marginal flanges engaging each other, one of the members having a depending cup portion and the other being resilient and having an elevated central projection engageable with the closure body, and vent means comprising a relatively restricted vent passage in said cup portion and a relatively restricted vent passage in said central projection, said inner cover projecting beyond the inner portions of the locking means of the closure body and being thereby retained in the latter.

10. In a closure structure, a cap body having means providing an air chamber, a relatively restricted vent passage adjacent the top of said air chamber, and a vent passage at the bottom of said chamber having a hood portion arranged to deflect fluid laterally toward the side of the chamber, said bottom vent passage being relatively large and adapted to permit relatively free drainage of liquid from said chamber.

11. In a closure structure, a cap body having means providing an air chamber, including an inner cap member having a depending cup por-

tion provided with a substantially flat bottom, a relatively restricted vent passage adjacent the top of said chamber, and a plurality of relatively large vent passages through said bottom and provided with hoods disposed to direct fluid laterally and substantially tangentially of the chamber.

12. In a closure device, a neck having an annular seat thereon and external locking cams depending from said seat, and a cap applied to said neck and comprising outer and inner cover members, the outer cover member having projections adapted to cooperate with said cams and the inner cover member extending beyond the inner portions of said projections whereby the inner cover member is retained in the outer cover member, said inner cover member having a central projection engaging the outer cover member and about which the cover members have relative rocking movement and having other portions normally spaced from the outer cover member but adapted to engage the same to limit said relative rocking, the spacing of said other portions from the outer cover member being approximately one-half the vertical distance between said seat and the starting portion of said cams when the cap is on the neck but prior to locking rotation thereof.

13. In combination, a neck having an annular gasket seat thereon and a vent passage inwardly of the gasket seat, a resilient washer extending transversely in the neck inwardly of said vent passage, and a closure adapted for releasable connection with the neck and having a gasket for engagement with said seat, said closure also having a portion adapted to extend into the neck for sealing engagement with said washer.

14. In combination, a neck having axially spaced outer and inner annular sealing portions and a vent passage therebetween, and a closure adapted for releasable connection with the neck with one part of the closure cooperating with said outer sealing portion, said closure having a hollow part adapted to extend into the neck in spaced relation to the wall thereof for engagement with the inner annular sealing portion, such hollow part of the closure having a check valve controlled opening leading thereto, and a vent passage adapted to be connected with the vent passage of the neck by the intervening space, said inner annular sealing portion being resilient and adapted to be deflected by said hollow part whereby yieldable sealing engagement is provided therebetween.
